(57) CLAIM

The ornamental design for a garment hanger, as shown and described.

DESCRIPTION

FIG. 1 is a front perspective view of a garment hanger showing our new design.

FIG. 2 is a front elevation view thereof. The rear elevation view is a mirror image of the front.

FIG. 3 is a left side elevational view thereof.

FIG. 4 is a right side elevational view thereof.

FIG. 5 is a top plan view thereof; and,

FIG. 6 is a bottom plan view thereof.

The broken lines shown in the drawings illustrate portions of the garment hanger that form no part of the claimed design.
